UNITED STATES PATENT OFFICE.

WALTER S. LUDLOW, JR., OF CINCINNATI, OHIO.

ELECTRIC ALARM SYSTEM.

1,411,112.

Specification of Letters Patent. Patented Mar. 28, 1922.

Application filed May 6, 1918. Serial No. 232,700.

To all whom it may concern:

Be it known that I, WALTER S. LUDLOW, Jr., a citizen of the United States, and residing at Cincinnati, in the county of Hamilton and State of Ohio, have invented a new and useful Improvement in Electric Alarm Systems, of which the following specification is a full disclosure.

My invention relates to a system for electric transmission of signals particularly adapted for central station watchman's time recording and fire alarm service.

For this particular class of signal service, single call boxes are used for both watchman's time recording or fire alarm signals, the advantage being that the transmitting mechanism and connecting lines are tested with each watchman's report signal to insure its being in order for transmitting an emergency or fire call. Thus constant check and supervision is had and the apparatus is always ready for an emergency. The signals from each box, whether report or fire signals, are received over the same apparatus at the central station, and although the signal indicating characters may be distinguishable, there is nothing to particularly call the attendant's attention quickly to an emergency or fire call.

With my invention I use the same transmitting device for the different species of calls, the advantage for regular testing of the lines and apparatus being maintained, but the fire or emergency calls are received and recorded over a special receiving apparatus in conjunction with the general receiving apparatus. The special receiving apparatus can be utilized for operating a sounder and also transmitting the emergency calls to the fire or police stations for direct notification service.

Therefore an object of the invention is to provide a central station electric signal service system with a plurality of signal receiving devices selectively responsive for general or report calls and collectively responsive for special or emergency calls with their operation controlled and affected by different current strengths or changes in current strength, so that the same impulse transmitting devices or call-boxes in circuit with the receiving devices may be used for the various kinds of signals and their character determined or distinctively recognized by the particular receiving device or the number of them operating at the same time. The cur-

rent strength is governed by resistance in the circuit line or lines, controlled through the call-box from which and at the time the signal is being transmitted.

Another object is to provide a signal service system of a combined watchman's time reporting and fire alarm class with a plurality of signal receiving instruments, the receivers influenced each by different current strength for a selective or combined response, enabling time reporting and fire alarm calls to be sent or transmitted from each call-box and the character of the call easily distinguished and determined by the number of receivers responding or reporting the calls, and which adapts itself for transmitting distinctive signals for the various kinds of calls from the same call-box.

Other features and objects of the invention, combination of elements and arrangements of parts, will be hereinafter more fully described, in connection with the accompanying drawings, forming a part hereof, and more particularly pointed out in the claim, in the drawings like characters of reference denote corresponding parts throughout the several views, of which:

Fig. 1 is a diagrammatic view of a signal system containing my improvements in the simplest form, and in a system having metallic and earth return circuits, and in which a common break wheel for each call transmits signals for general and special significance.

Fig. 2 is a modified form over Fig. 1, in which separate break wheels for each call-box are used to transmit the general and special calls.

Fig. 3 is another modified view over Fig. 1, in which two earth return circuits are used, one normally closed and the other open.

As the system primarily is contemplated for a central station night watch time reporting and recording and firm alarm signal service, the description generally will be confined to this particular field of use, although comprehending a wider field of use, wherein it may be desired to transmit signals distinguishable at a receiving point as to their character or kind for various service utility.

The line or field circuit or circuits may compare to those now generally prevailing for watchman's reporting and fire-alarm service, as an all-metallic circuit line

with divisional earth return circuits to the central station or receiving point from each call-box, for normally transmitting two distinctive signals from each call-box or transmitting point, and the distinctive signals may be designated open and closed circuit signals. The systems also include features for testing and establishing a circuit in the event of break or ground trouble on the metallic line.

The system may also be of a class in which two distinctive circuits are established for signal transmission, each circuit having an earth return to the central station or receiving point, the receiving relays in said circuit being operative by a change in the current strength, and alternate opening and closing of the circuit.

The same signal or break wheels may be utilized for both general and special signals or separate break wheels rotating as a unit for each, within the aspects of this invention. In the latter instance, however, it is preferable to cut off the one during the active or transmitting period of the other to avoid a confusion of signals on any and all of the receiving relays.

As systems of this class must to a degree meet and comply with rules and requirements regarded as license regulations, differing in different localities, a definite wiring arrangement or scheme cannot be universally followed and which primarily is due to the various kinds or styles of transmitting apparatus recommended and approved in different localities.

Thus the different modifications of systems illustrated in the drawings follow those most commonly prevailing and generally approved standards with which my improvements are readily combined.

Referring to Fig. 1 of the drawings, 1, 2, 3, indicate signal receiving relays each of a common type comprising an electromagnet 45 coil 4, armature 5, swinging between contacts 6 and 7, in some instances one of the contacts serves as an adjustable stop pin. A retractile spring 8, regulatable at 9, is provided for moving the armature away from the electro-magnet. On the energizing of the electro-magnet, provided the resistance of the spring 8 is not greater than the pull of the magnet, attraction of its armature closes the contact 6, completing the circuit of a local battery or generator leading to and connecting with signal printing or recording apparatus, for controlling and operating said apparatus.

Relay 1 may be designated as a prime or 60 first relay, relay 2 as a supplemental or second, having the tension of its spring 8 set to a tension so as to require a different or increase in the current strength over that required for relay 1, for its electro-magnet to attract its armature lever.

Likewise relay 3 is set to require an increase in current strength over both relays 1 and 2 before its electro-magnet will attract its armature lever. The relays 1, 2 and 3 are connected in series with one another and thus under a normally closed circuit, relay 1 will stand with its armature lever attracted to its electro-magnet, while relays 2 and 3 will stand open or with their armature levers in a retracted position away from their electro-magnets.

10 indicates a combined watchman's and fire-alarm call-box of which there may be any number connected in series and for the present purposes only one of such boxes is included in the system.

These call-boxes, as far as their control or method of operation for sending a call is concerned, correspond to those now in commercial use. They contain clock mechanism for revolving a break or signal wheel and for a watchman's or general call are controlled by a key and for a fire or special call by the pull of a lever. The latter is usually protected by a glass which must be broken to gain access to the lever. For a watchman's or general call, the operator inserts a key and therewith starts or cranks the clock mechanism for imparting, say a single revolution of the break wheel, while with a control through the operation of the pull lever, a plurality of break wheel cycles will be had. Thus a single break wheel may be employed and the class of signal or call distinguished at the receiving point by the number of times the signal is transmitted. The principle of differential break wheel cycle for distinguishing one kind of a signal from another, whether one or a plurality of different break wheels are employed, is utilized in the various modifications herewith included as a part of this specification.

Now continuing to refer to Fig. 1, 12 indicates the clock mechanism operated in one instance by a key 11 for one kind or general call and by the pull lever 13 for a second kind or special call, it being understood that with the key control the break wheel 14 is given one revolution and with the pull lever control the break wheel is given a plurality of revolutions, and for the present purposes, say three revolutions.

The pull lever may, as in some types of call-boxes, be automatically reset, but as their general details of construction are well known and understood in the art, no specific disclosure need be made herein.

Three flexible contact fingers 15, 16, 17, are relatively arranged and insulated from one another with the intermediate finger 16 extended to engage the periphery of the break wheel 14, so as to be movable to alternately make contact with fingers 15 and 17. The break wheel 14 is notched or toothed for a proper finger control, to transmit a definite

signal by making and breaking the open and closed circuits to each break wheel cycle or revolution.

The break wheel in its idle position is arranged for holding the fingers 16 and 17 in contact to complete the closed circuit line with the receiving point or station. The pull lever 13 connects with a contact member 19, making contact with a contact terminal 20. The contact terminal 20 connects through a wire 21, with the wire 22, connecting with the break finger 15. The wire 22 connects with one pole of the resistance 23 and the opposite pole of the resistance 24 connects with the wire 24, leading to the ground 25. A wire 26 connects wire 24 with the said member 19. Under normal condition of the system, the switch member 19 stands open, so that the resistance connects in circuit with the break finger 15 and the resistance is shut or cut out of circuit when the switch member 19 is closed, and a closing of the switch member 19 is accomplished when operating the pull lever 13.

The relays 1, 2 and 3 located in a central serial station or receiving point have their electro-magnets connecting in series with each other and connect through a wire 27 with the break finger 16. The relays from an opposite pole connect with a resistance 28 and one terminal or pole of the battery or generator 29. The opposite pole of the battery or generator 29 has a ground lead 30 and also connects with the field wire line 31, which includes in series therewith a resistance 32, and said field line 31 connects with the break finger 17 of the last call-box of the series in the system, and the fingers 16 and 17 of all of the call-boxes connect in series through one another to close or connect field wire 27 and 31.

It should be observed that the metallic line provides a normally closed circuit under which relay 1 has its armature attracted, and relays 2 and 3 have their armature levers in a retracted position, their electro-magnets are energized, but the current strength by reason of the resistance 28 and 32, is lowered so that the energizing pull of the electromagnets 2, 3, is not great enough to counteract the pull of the springs of the armatures of the relays 2, 3.

For a general or watchman's signal, a break wheel 14 is rotated, which for signal transmission makes and breaks the circuit through fingers 16 and 17, and also makes and breaks the circuit through fingers 15 and 16. When the fingers 15 and 16 are brought into contact with each other, the circuit has an earth return from the call-box, and is completed through the following course:—

From the relays 1, 2, 3, field line 27, contact fingers 16, 15, wire 22, resistance 23, wire 24, ground 25, through the earth to

ground lead 30, generator 29, resistance 28 and opposite pole of relays 1, 2, 3, connected in series.

During such period, the metallic line 31 and the resistance it carries, is cut out so that the strength of current passing through the electro-magnets of the relays is increased and to a degree increases the magnetic pull of the electro-magnet of relay 2, and attracts its armature, overcoming the resistance of the spring tension. Relay 3, however, will not be affected, because the circuit still carries sufficient resistance, preventing its magnet from exerting a pull sufficient to overcome the resistance of the spring connecting with its armature. This can only be eliminated by cutting out the resistance 23 and which can only be accomplished through the pull lever 13.

For transmitting a special or fire-call, the pull lever 13 is thrown, to start or crank the clock mechanism. Such operation closes switch 19, with contact 20, shunting or cutting out the resistance 23 in the earth return of the circuit, whereupon when break fingers 16 and 15 are in contact, relay 3 will attract its armature lever and respond to the signal impulses in conjunction with relays 1 and 2.

Therefore for a general alarm, relays 1 and 2 are operated and for a special alarm, relays 1, 2 or 3, or all are operated, each receiving the same signal, but when relay 3 operates, the central station immediately recognizes that a special or fire signal is being transmitted, although the signal number or indication is the same for either general or special alarms.

The modification shown in Fig. 2 employs a special signal break-wheel 33 rotating as a unit with the general break-wheel 14. It will be observed that the switch member 19 alternately engages with two contact terminals 20 and 20^a. Terminal 20^a connecting with the break finger 15 of the general break finger 14, through a wire 22, which includes the resistance 23 in series therewith, while contact terminal 20 connects with a wire 34 leading to and connecting with a break finger 35 of the special break wheel 33. The finger 35 makes contact with finger 16^a engaging break-wheel 33 and is in circuit connection with the field line 27 and to which finger 16 of the general call break-wheel 14 connects.

A control of signal transmission from either general call break-wheel 14 or special call break-wheel 33 is through the relative position of the pull lever 13. For general calls, the break fingers 35 and 16^a are cut out of circuit, while for a special call, the break fingers of the general call break-wheel 14 are cut out of circuit and likewise the resistance 23. In this form, the general and special calls are distinctive of one another. Re-

lays 1 and 2 respond to a general call and relay 3 responds with the others when the call is made upon throwing the pull-lever 13.

The control and operation of the break wheels are substantially the same as that described in the form illustrated in Fig. 1. The system diagram, shown in Fig. 3, may be regarded as substantially the same as that in Fig. 2, except that the two circuit lines 10 each have an earth return, no complete metallic circuit being employed.

Having described my invention, I claim:

A signaling system comprising a normally closed metallic circuit, a plurality of signal 15 receiving electrical devices connected in series in the signaling circuit, the said devices being responsive to relatively different strengths of electric current, a resistance in the circuit rendering two of said devices nor-

mally inoperative, a call box in the circuit, 20 a ground return circuit from the call box to the receiving devices, including a second resistance and shunting out of the said first resistance, means for transmitting signal impulses through the ground circuit to operate 25 one of said two devices, and means for shunting out said second resistance and thereby allow the transmission of signal impulses which will operate all of the signal receiving devices.

In witness whereof, I hereunto subscribe my name, as attested by the two subscribing witnesses.

WALTER S. LUDLOW, JR.
